UNITED STATES PATENT OFFICE.

RICHARD ALEXANDER-KATZ, OF CHARLOTTENBURG, AND ALFRED KARFUNKEL, OF BERLIN,
GERMANY.

PLATE FOR COOLING APPARATUS.

No. 892,108.

Specification of Letters Patent.

Patented June 30, 1908.

Application filed January 21, 1907. Serial No. 353,317.

To all whom it may concern:

Be it known that we, RICHARD ALEXANDER-KATZ, and ALFRED KARFUNKEL, both subjects of the King of Prussia, and residing 5 at Charlottenburg, near Berlin, Germany, and Berlin W., Germany, respectively, have invented certain new and useful Improvements in Plates for Cooling Apparatus, of which the following is a specification.

10 This invention relates to a hollow metal plate combining great strength with lightness and with specific properties enabling it to be used for many purposes in building, machine construction and in cooling apparatus.

15 The improved plate comprises two parallel members of thin sheet metal punched at small and regular intervals so that short, tubular bosses project therefrom. The bosses projecting from one of these members are of somewhat smaller diameter than the bosses of the other member, the difference between the diameters being approximately equal to twice the thickness of the metal. The members thus prepared are placed together so that the narrower bosses are opposite the wider bosses, and are then powerfully pressed 20 towards each other so that the bosses of smaller diameter are forced into those of larger diameter. The edges of the sheet metal may then be bent over at two, three or all four sides in order to close the composite plate formed or other means may be used for closing the said plate. By dipping the composite plate into molten metal, for example 25 tin, lead, zinc, or an alloy, the small orifices and interstices are filled up, more particularly at the joints between the bosses.

30 The invention is illustrated in the annexed drawing by means of examples, Figures 1 and 2 being respectively an elevation and a cross-section of a portion of a plate constructed in the manner described; Figs. 3 and 4 are respectively a front view and cross-section of a motor-car radiator consisting of 35 groups of hollow plates placed at an angle relatively to each other.

In Figs. 1 and 2 *a* and *a'* represent the two sheet metal members, and *b* and *c* the smaller 40 and larger bosses respectively forming the composite plate *d*.

The composite plate described possesses great strength and durability relatively to its bulk and weight, since the bosses act as stays,

and the parallel sheet metal members oppose great resistance to bending strains. The strength of the plate is greatly increased by soldering the joints between the bosses. The properties possessed by the plate enable it to be used with great advantage in all structures in which the combination of strength with lightness is essential, as for example in motor-cars and air-ships. Another advantage of the plate lies in the large surface area thereof relatively to the space occupied; this advantage is more particularly of value for the construction of cooling apparatus, and the like. The immersion of the plate in molten metal renders the joints between the tubular bosses watertight and steam-tight.

Very efficient cooling-apparatus for explosion-motors, brewing purposes and the like can be constructed as shown in Fig. 3 by arranging a group of parallel hollow plates *d*, produced in the manner described, in communication with a water supply conduit *e* and discharge conduit *f* common to all the plates.

The efficiency of the apparatus is improved if the plates *d* are so placed that the tubular ducts in consecutive plates are not in line with each other, so that the cooling agent, for example cold air, alternately flows through the ducts and impinges on the walls of sheet metal. This arrangement of the ducts is, for example, secured by placing the plates in the inclined positions illustrated in Fig. 4.

It is obvious that exceptionally good cooling effects are obtainable by reason of the large cooling surface available, the rapid transfer of temperature due to the thinness of the sheet metal, and the multiplicity of paths afforded to the cooling agent. The efficiency of the apparatus is probably superior to that of any cooling apparatus hitherto known.

What we claim as our invention and desire to secure by Letters Patent of the United States is:—

1. A hollow metal plate consisting of parallel members of sheet metal, and a plurality of uniformly distributed tubular bosses punched out of each of said members, the bosses of the one member being somewhat smaller than and fitting within the bosses of the other member, and the outer edges of said larger bosses being in contact with

the inner face of the member carrying the smaller bosses substantially as set forth.

2. A hollow metal plate consisting of parallel members of sheet metal, and a plurality of uniformly distributed tubular bosses punched out of each of said members, the bosses of the one member being somewhat smaller than and fitting within the bosses of the other member, the outer edges of said 10 larger bosses being in contact with the inner face of the member carrying the smaller bosses, and a layer of sealing metal disposed over the entire plate substantially as described.

3. Cooling apparatus comprising in combination a plurality of hollow metal plates each consisting of parallel members of sheet metal, and a plurality of uniformly distributed tubular bosses punched out of each of said members, the bosses of the one member being somewhat smaller than and fitting within the bosses of the other member, the outer edges of said larger bosses being in contact with the inner face of the member carrying the smaller bosses and fluid supply and

discharge conduits in communication with said plates substantially as described.

4. Cooling apparatus comprising in combination a plurality of hollow metal plates each consisting of parallel members of sheet 30 metal, and a plurality of uniformly distributed tubular bosses punched out of each of said members, the bosses of the one member being somewhat smaller than and fitting within the bosses of the other member, the 35 outer edges of said larger bosses being in contact with the inner face of the member carrying the smaller bosses, and a layer of sealing metal disposed over the entire plate and fluid supply and discharge conduits in communication with said plates substantially as described.

In witness whereof we have signed this specification in the presence of two witnesses.

RICHARD ALEXANDER-KATZ.
ALFRED KARFUNKEL.
